UNITED STATES PATENT OFFICE.

CHARLES S. BOLL, OF HARRISBURG, PENNSYLVANIA.

DESIGN FOR HEAD OR FOOT SECTION FOR BEDSTEADS.

SPECIFICATION forming part of Design No. 36,191, dated January 13, 1903.

Application filed July 23, 1902. Serial No. 116,743. Term of patent 7 years.

To all whom it may concern:

Be it known that I, CHARLES S. BOLL, a citizen of the United States, residing at Harrisburg, in the county of Dauphin and State of Pennsylvania, have invented a new, original, and ornamental Design for Head or Foot Sections for Bedsteads, of which the following is a specification, reference being had to the accompanying drawings, in which—

10 Figure 1 is a perspective view of a head or foot section of a bedstead made in accordance with my design. Fig. 2 is a perspective view of the same viewed from the other side. Fig. 3 is an end elevation.

15 Referring now to said drawings, it will be noticed that the head or foot section is formed in the main part of one continuous piece of tubing A, which comprises two substantially vertical portions B and C, rising from collars 20 D, located above the standards E, resting on the usual casters. Between the vertical portions of the tubing are vertical rods F, supported by a cross-rod G at their lower ends.

As will be clearly seen from my drawings,

the large vertical portions B and C of the continuous tubing and the vertical rods F are all bent slightly outward at their upper ends. 25

The ornamental feature in my design consists in a head or foot section wherein the whole of the section, including the continuous 30 tubing and the vertical rods F, is formed on an outward curve at the upper end, which makes a very attractive though simple form of ornamentation.

Having described my design, what I claim 35 as new is—

The ornamental design for a head or foot section of a bedstead as herein shown and described.

In testimony whereof I hereby sign my 40 name to this specification, in the presence of two subscribing witnesses, this 15th day of July, 1902.

CHARLES S. BOLL.
